United States Patent Office.

E. E. WORDEN AND H. WILMS, OF BRANDON, VERMONT.

Letters Patent No. 74,872, dated February 25, 1868.

IMPROVED SPRING-BED BOTTOM.

The Schedule referred to in these Letters Patent and making part of the same.

TO ALL WHOM IT MAY CONCERN:

Be it known that we, E. E. WORDEN and H. WILMS, of Brandon, in the county of Rutland, and State of Vermont, have invented a new and improved Spring-Bed Bottom; and we do hereby declare that the following is a full, clear, and exact description thereof, which will enable others skilled in the art to make and use the same, reference being had to the accompanying drawings, forming part of this specification.

This invention relates to a new and improved method of constructing spring-bed bottoms, and it consists in the use of elliptic springs or stays, and in the manner in which the upper frame is supported thereby, and also in the manner in which the spiral springs are supported and held in position, as will be hereinafter more fully described.

Figure 1 represents a top view of a bed-bottom formed according to our invention.

Figure 2 is a vertical end view of the same, showing the supporting elliptic spring between the frames, and the manner in which the spiral springs are connected and supported.

Similar letters of reference indicate corresponding parts.

A represents the base or lower frame, formed of two (more or less) longitudinal pieces *a a*, and more or less transverse slats *b*, by which the pieces *a* are connected in the usual manner. Above the frame A there is another frame B, which, in this example of our invention, is made of metallic rods. C represents elliptic springs or stays, two or more of which are placed between the two frames for the support of the outer edges. These springs are formed of two pieces, each connected together, as seen in the drawing, with the ends of the upper piece extending each way on the lower frame for steadyng and supporting the upper frame and spiral spring where it is secured to the frame by bolts or screws, which pass through slots *d*, so as to allow of its expansion. The spring or stay C is also connected with the lower frame at *e*, and to the upper frame at *f*, as seen in the drawing. D represents the spiral springs, which are placed upon the lower frame and connected together, and to the upper frame by cord or wire diagonally across the top of the springs, as seen in the drawing. And in addition to this support, the cord or wire is passed alternately from the top to the middle of the springs, so that the centre or weaker portions of the springs are supported, and the springs kept in an upright position. This method of connecting and securing the spiral springs is clearly shown in fig. 2. By the application of two or more elliptic stays or springs C, lateral motion is prevented, which counteracts the tendency of the spiral springs to sway from an upright position. It will be seen that the upper and the lower frames are connected by spiral springs near their extreme outer edges, thereby giving elasticity to the edge. These spring-bottoms may be made of any suitable materials, and the elliptic springs or stays may be attached to the upper frame in any suitable manner.

Having thus described our invention, what we claim as new, and desire to secure by Letters Patent, is—

The stays C, supporting the outer edges of the frames A B, the ends of the upper piece of the stay slotted to slide upon pins in the lower frame, and connected at its centre, *f*, to the upper frame, the lower piece of said stay secured at its centre to the lower frame, and at its end to upper piece, all operating as described for the purpose specified.

The above specification of our invention signed by us, this 8th day of October, 1867.

E. E. WORDEN,
H. WILMS.
